Application February 11, 1944, Serial No. 521,896

6 Claims. (Cl. 318—286)

1

My invention relates to apparatus for control of highway crossing gates, and more particularly to apparatus for automatic control of highway crossing gates.

An automatic highway crossing gate is ordinarily controlled by trains through the medium of track circuits. The gate arm is latched in a raised or non-obstructing position as long as the approach track sections are unoccupied and is moved to a lowered or obstructing position across the highway in response to a train entering an approach track section. When a train has passed beyond the intersection, the gate arm is raised to its non-obstructing position unless a second train or some other traffic condition makes it unsafe for highway traffic to pass over the intersection. Such automatic control of a highway crossing gate must include safeguards wherewith the lowering of the gate arm is not prevented by high winds or other conditions, and mechanical shock and rebound of the arm at the lowered position are avoided. Also, a circuit arrangement that is reliable, efficient and of minimum structure is essential.

In view of such circumstances, a feature of my invention is the provision of improved apparatus for control of highway crossing gates.

A further feature of my invention is the provision of control apparatus for highway crossing gates incorporating novel and improved means for power driving the gate arm both up and down, to deenergize the slot magnet while the motor is operated to drive the gate down, to cushion the movement of the gate arm at the lowered position, to avoid lowering the gate arm from an intermediate position and to minimize the circuit and control apparatus without sacrifice of safety and efficiency.

Other features, objects and advantages embodying my invention will appear as the specification progresses.

The above features, objects and advantages of my invention I attain by providing a novel and improved arrangement of circuits and apparatus for a gate mechanism which includes a motor, a slot magnet and a circuit controller. The motor is operatively connected through a suitable gear train to the gate arm which is movable between a lowered or obstructing position and a raised or non obstructing position. The gate is counterbalanced for the arm to gravitate to its lowered position but I preferably provide a reversible motor which is reversibly energized through a pole changing means to power drive the gate arm up and down according to the position of the

2

pole changing means as predetermined by a main control device. That is, the motor is operated in one direction in opposition to the bias to raise the gate arm and is operated in the opposite direction to aid the bias in the lowering of the gate arm.

In the raising of the gate arm the motor is disconnected from the current source at a contact of the controller opened at substantially the full raised position of the arm. In the lowering of the arm, the motor preferably is supplied with power during a preselected first portion of the movement, and is disconnected from the current source and is included in a low resistance circuit path or "snubbing" circuit during the final portion of the lowering movement to effect a dynamic braking, such switching of the motor circuits being accomplished through the medium of contacts of the circuit controller. In this way the lowering of the arm is not prevented or delayed due to high winds and other conditions that may oppose the gravity bias and mechanical shock and rebound of the arm at the lowered position are avoided.

Again, the counterbalance of the arm may be such that the motor need not be powered only for a preselected portion of a downward movement and then disconnected from the current source and the arm allowed to continue the movement under the force of the bias, the "snubbing" circuit being omitted. Preferably the control circuits would include a stick circuit arrangement wherewith once the raising of the gate arm is initiated the motor is operated independent of the main control until the full raised position is reached, at which point the main control is again made effective. This prevents the gate arm from being lowered from an intermediate position in front of or on top of a highway vehicle that may have started across the intersection upon the driver observing the gate arm starting to raise.

The slot magnet is preferably of the double winding type having a holding winding and a pick-up winding, the magnet armature being lifted to its latching position only when both windings are energized but retained at its latching position by the energization of the holding winding alone. The holding winding is controlled through a contact of the main control device and current is removed from the slot magnet at the same time current is supplied to the motor to drive the gate arm downward. This prevents the slot latch from being forced in its released position by the motor. The circuit for the pick-up winding is carried through two controller contacts in series, the first one of which two contacts is the

contact used to open the motor circuit at the raised position. The second one of these two contacts is closed just shortly before the first mentioned contact is opened. This first controller contact is of a construction that it is reclosed during the lowering movement of the arm at a position further removed from the raised position than the point at which such contact is opened during the raising of the arm and the point at which it is reclosed is made subsequent to the opening of the second one of the two contacts. In this way energization of the pick-up winding before the motor is energized to raise the arm is avoided in case the arm is being lowered and the main control is changed to that for raising the arm. Thus, the motor is made to take the shock and stress of arresting the lowering movement of the gate arm rather than the slot magnet when a change of control occurs while the arm is being lowered.

Again, the "snubbing" circuit includes a contact which is held open when the motor is powered to drive the gate arm downward as well as a contact held open when the motor is powered to raise the arm.

Furthermore, when the gate mechanism is of the type provided with a case suitable for housing relays, I locate one or two of the control relays in the mechanism to minimize the circuit wiring.

I shall describe three forms of apparatus embodying my invention, and shall then point out the novel features thereof in claims.

In the accompanying drawings, Figs. 1, 2 and 3 are diagrammatic views showing three different forms of apparatus for automatic control of highway crossing gates by trains, and each of which forms of apparatus embodies my invention. Fig. 4 is a chart showing the positions at which controller contacts of the gate mechanisms of Figs. 1, 2 and 3 are opened and closed.

In each of the several views like reference characters are used to designate similar parts.

It is to be understood that apparatus embodying my invention is not limited to automatic control of highway crossing gates by trains and it is useful with apparatus where the gate is manually controlled and where the gate is controlled in part manually and in part by railway traffic.

Referring to Fig. 1, the reference characters 1a and 1b designate the track rails of a railway intersected at grade by a highway H, and at which intersection two highway crossing gates G1 and G2 are located. The track rails are formed by the usual insulated rail joints with two track sections, one on each side of the highway, a section D—E being formed to the left of the highway H as viewed in Fig. 1, and a section E—F being formed to the right of the highway. In other words, section D—E is an approach section for eastbound trains and section E—F is an approach section for westbound trains.

Each track section D—E and E—F is provided with a track circuit which includes a current source, such as a battery 10, connected across the rails at one end of the section, and a winding of an interlocking relay IR connected across the rails at the other end of the section, winding 11 of relay IR being included in the track circuit of section D—E and winding 12 of relay IR being included in the track circuit for section E—F. The connections of windings 11 and 12 to the track rails are those of common practice to provide the so-called "extended shunt" protection, as will be readily understood by an inspection of

the drawings, and these connections need not be described in detail since they form no part of my invention.

Highway crossing gates G1 and G2 are shown conventionally and are located one on each side of the railway tracks and are adaptable of being operated in a manner such that their respective gate arms 13 and 14 are moved between a lowered position where the arm extends horizontally across at least a portion of the highway H and a raised position where the arm extends substantially vertical. Each crossing gate G1 and G2 is provided with an operating mechanism which may be any one of several well-known types and preferably the two mechanisms are of like construction. In the present embodiment of the invention the mechanism for each gate G1 and G2 is similar to that shown and described in Letters Patent of the United States No. 1,138,087, granted to John P. Coleman on May 4, 1915, for Railway signals, and to which patent reference is made for a full understanding of the construction of such mechanism. In the application the gate arm is an extended form of the semaphore of the patent.

The mechanism and control for gate G1 only is shown in the drawing for the sake of simplicity since the two gates are alike and the mechanism and control of gate G2 would be a duplication of that for gate G1.

Looking at the gate G1 mechanism of Fig. 1, a motor M1, slot magnet SM and a circuit controller C1 are among the essential elements of the mechanism. Motor M1 is a direct current reversible motor having an armature 15 and a field winding 16. Motor M1 is operatively connected by suitable drive mechanism (not shown) to the gate arm 13 and which drive mechanism may be similar to that disclosed in the aforementioned Coleman patent. The mechanism of gate G1 is counterbalanced for arm 13 to be gravity biased to the lowered position. Motor M1 when supplied with current which flows in its armature in one direction with respect to the flow of current in the field winding is operated as required to raise the arm 13 against the bias force. When motor M1 is supplied with current that flows in its armature reverse with respect to said one direction, the motor is driven as required to lower the arm, the motor M1 aiding the bias force. In the following description the position of the gate mechanism corresponding to the lowered or obstructing position of the gate arm will be at times referred to as a zero degree or obstructing position, and the position of the gate mechanism corresponding to the raised or non-obstructing position of the gate arm will be at times referred to as a 90 degree or non-obstructing position. It will be understood, however, that apparatus embodying my invention is not limited to a 90 degree movement of the gate arm. Also, it is to be observed that the arm may be provided with a slightly greater than 90 degree movement in order to permit adjustment.

Slot magnet SM includes a holding winding 17, a pick-up winding 18 and an armature 35. As fully explained in the aforementioned Coleman patent, the armature 35 when picked up latches the gate arm at the 90 degree position, and when the magnet is deenergized and the armature released, the gate mechanism is free to move toward its zero degree position. The arrangement is such that the armature 35 is raised to its attracted and latching position only when both windings 17 and 18 are energized, but once

picked up the armature is held at its latching position by the energization of the holding winding 17 alone.

Controller C1 includes a series of contacts 2, 3, 4, 5 and 6, which are shown conventionally for the sake of simplicity. The controller C1 is operatively connected to the gate arm through the gate mechanism in such a manner that the contacts are opened and closed as indicated by the chart of Fig. 4. It is to be observed that contact 4 of the controller is opened at the 89 degree position in the raising of the gate arm and is not reclosed until the 83 degree position of the arm when the arm is being lowered. The function of such construction of contact 4 will be pointed out more specifically later in the description. The construction of contact 4 may be that disclosed and claimed in Letters Patent of the United States No. 2,363,936, granted November 28, 1944, to H. L. Bone, for Circuit controllers.

The control means for the gate G1 of Fig. 1 includes a track repeater relay or control device TPR, a control relay XR and two other relays DN and SN. Repeater relay TPR is a slow release direct current relay energized by current supplied from a source, the terminals of which are indicated at B and C, the energizing circuit being completed through flagman contacts 19 and 20 in series of the interlocking relay IR. It follows that when both sections D-E and E-F are unoccupied or either section is occupied by a train receding from the intersection and the other track section is unoccupied, repeater relay TPR is energized and picked up, but that when either section is occupied by a train approaching the intersection the relay TPR is deenergized. Repeater relay TPR governs the control relay XR and the holding winding 17 of the slot magnet by obvious circuits which include front contacts 9 and 21 of relay TPR, respectively. The two relays DN and SN are preferably of the type that permits their being located in the gate mechanism. Control relay XR governs the two relays DN and SN, the pick-up winding 18 of slot magnet SM and the motor operating circuits, the control of these devices being effected in part through contacts of the circuit controller C1. It is believed that these various circuits will best be understood by a description of the operation of the apparatus of Fig. 1.

Normally, that is, when both track sections D-E and E-F are unoccupied, the interlocking relay IR is picked up to close the circuit for repeater relay TPR and that relay is picked up to close front contacts 9 and 21 and thereby complete the circuits for the control relay XR and the holding winding 17 of the slot magnet. Such energization of the slot magnet winding is effective to retain the gate mechanism at its 90 degree position, it being understood that the mechanism has been operated to that position in a manner to appear shortly.

Assuming an eastbound train enters the approach section D-E, winding 11 of the interlocking relay IR is shunted and its armature is released to open front contact 19 and close back contact 22. The opening of front contact 19 deenergizes repeater relay TPR and that relay releases at the end of its slow release period. In accordance with standard practice, the closing of back contact 22 of relay IR completes a warning signal circuit by which a warning bell or lamp, or both, are operated to warn highway users that a train is approaching and that the gate arm is about to be lowered. The remaining portion of

such warning circuit is omitted for the sake of simplicity since it would be in accordance with standard practice and forms no part of my invention. It is to be noted, however, that such warning signal would be set into operation immediately upon the train entering the section D-E, whereas the release of relay TPR which governs the lowering of the gate is delayed due to the slow release period provided for relay TPR.

10 The release of relay TPR to open front contacts 9 and 21 deenergizes control relay XR and holding winding 17 of the slot magnet with the result that relay XR is released and the gate arm is unlatched and is free to be moved to its horizontal position. Since the gate is normally counterbalanced its arm will gravitate toward its lowered position by virtue of its own weight. However, the release of relay XR to close back contacts 23 and 24 completes a circuit for relay DN and prepares an operating circuit for the motor M1. The circuit for relay DN extends from terminal B of the current source through back contacts 23 and 24 in multiple of relay XR, controller contact 3 closed for a preselected portion of the downward movement of the gate arm, and winding of relay DN to terminal C. Relay DN is energized and picked up to complete an extension of the circuit which forms the motor circuit, and current flows from terminal B through back contacts 23 and 24 in multiple, controller contact 3, front contact 25 of relay DN, armature 15 of motor M1 from right to left as viewed in Fig. 1, front contact 26 of relay DN and motor field winding 16 to terminal C. The connections for the motor M1 are such that the motor is now energized and operated as required to power drive the gate arm in its downward direction, such operation of the motor being effective to move the gate arm even though a high wind and other conditions may exist that would tend to retain the arm at the raised position against the bias force. When the 45 degree position is reached and controller contact 3 is opened, this circuit for relay DN and motor M1 is opened, but the gate arm continues to move toward its lowered position under the influence of the bias.

With the release of relay DN a "snubbing" circuit is completed from the left-hand terminal of armature 15 of motor M1 through back contact 27 of relay DN, back contact 29 of relay SN, a resistor 30, field winding 16, and back contact 28 of relay DN to the right-hand terminal of armature 15. Since armature 15 is now driven by the bias force the motor M1 functions as a generator to brake the movement of the gate arm, the braking force exerted being predetermined by the adjustment of resistor 30.

At the 10 degree position in the lowering movement of the gate, the contact 2 of circuit controller C1 is closed and a short circuit path can be traced from the left-hand terminal of armature 15 of motor M1 through back contact 27 of relay DN, back contact 29 of relay SN, controller contact 2, field winding 16, back contact 28 of relay DN and to the right-hand terminal of armature 15. Since motor M1 is now substantially short circuited the dynamic braking is increased so that at the zero degree position of the arm no severe mechanical shock or rebound of the arm takes place.

The gate arm remains at its lowered position until the train passes beyond the intersection and the rear end of the train vacates section D-E permitting winding 11 of relay IR to be reener-

gized. The closing of front contact 19 of winding 11 completes the circuit for relay TPR and that relay is energized to close front contacts 9 and 21 and complete the circuits for control relay XR and winding 17 of the slot magnet. With control relay XR picked up to close front contacts 31 and 32, a circuit is formed for relay SN and a motor operating circuit is prepared, the circuit for relay SN including terminal B, front contacts 31 and 32 in multiple, controller contact 4, winding of relay SN and terminal C, and relay SN is picked up to close front contact 33. The closing of front contact 33 of relay SN completes an extension of the circuit which forms a motor operating circuit so that current flows from terminal B through front contacts 31 and 32 in multiple, controller contact 4, front contact 33 of relay SN, back contact 27 of relay DN, armature 15 of the motor from left to right, back contact 28 of relay DN, and motor field winding 16 to terminal C. The motor M1 is now operated as required to raise the gate arm against the bias force.

When the arm is raised to the 86 degree position the controller contact 5 is closed and current flows from terminal B through front contacts 31 and 32 of relay XR in multiple, controller contacts 4 and 5 in series and pick-up winding 18 of slot magnet SM to terminal C, and the armature 35 of the slot magnet is raised to its latching position since both windings 17 and 18 are now energized.

At the 89 degree position in the raising movement of the gate, the controller contact 4 is operated to open the circuits for relay SN, motor M1 and pick-up winding 18, with the result relay SN is released, the operation of the motor is discontinued and the gate arm is retained latched in its raised position due to the energization of the holding winding 17.

It is to be pointed out specifically that the circuit for energizing pick-up winding 18 of the slot magnet includes the controller contacts 4 and 5 in series, the circuit being completed between the 86 degree and the 89 degree movement in the raising of the gate arm. Then, when the gate is being lowered, contact 5 is opened at the 86 degree position but contact 4, due to its construction, is not reclosed until the 83 degree position, and the circuit for winding 18 is not closed at any point during the lowering of the arm. Consequently, if the gate is being lowered and the main control should be changed to that for raising the arm, the stress due to stopping the movement of the arm is taken up by the motor and not by the slot magnet, and which stress might be great enough to damage the slot magnet.

It is also to be observed that when control relay XR is picked up in response to the picking up of relay TPR, a stick circuit is completed for relay XR, which circuit extends from terminal B through controller contact 6, front contact 34 of relay XR and winding of that relay to terminal C. Consequently, once relay XR is picked up by the main control, that is, through contact 9 of relay TPR, and the gate arm is started to raise, relay XR is retained energized independent of relay TPR and the raising movement of the gate is continued until the 89 degree position is reached and controller contact 6 is opened. In other words, once the raising of the gate arms is started subsequent to a train passing beyond the intersection, the gate arm is raised to its vertical position before it can be again lowered in response to a second train entering the approach.

section. In this way the gate arm is not lowered from an intermediate position to come down on top of some highway vehicle that has started over the intersection after waiting for the first train to pass.

Again, it is to be observed that the "snubbing" circuit is held open at back contact 27 of relay DN during the lowering of the arm under the influence of motor M1, and is held opened at back contact 29 of relay SN during the operation of the motor in raising the gate arm.

It is apparent that the operation of the apparatus of Fig. 1 for a westbound train is similar to that described for an eastbound train, except that the relay TPR is controlled at front contact 20 of winding 12 of the interlocking relay.

In Fig. 2, the track layout and the control of repeater relay TPR, control relay XR and holding winding 17 of slot magnet SM are the same as in Fig. 1 except the stick circuit for control relay XR is omitted. The circuit for relays DN and SN and motor M1 of Fig. 2 are arranged for the two relays DN and SN to function as a pole changing means, the "snubbing" circuit for the motor being omitted. It is believed that the circuits of Fig. 2 will best be understood by a description of the operation of the apparatus.

Normally, that is, when both sections D—E and E—F are unoccupied, the repeater relay TPR is picked up to close front contacts 9 and 21 and the control relay XR and holding winding 17 are energized, the energization of winding 17 latching the gate arm at the 90 degree position.

An eastbound train entering section D—E of Fig. 2 to shunt winding 11 of the interlocking relay brings about the deenergization of repeater relay TPR and the operation of the warning signal. Relay TPR releases at the end of its slow release period, to cause control relay XR and holding winding 17 to be deenergized with the result the gate arm is unlatched and is free to be moved to its lowered position. The release of relay XR to close back contacts 23 and 24 completes a circuit which includes in series the winding of relay SN and motor M1, such circuit extending from terminal B through back contacts 23 and 24 of relay XR in multiple, controller contact 3, winding of relay SN, armature 15 of motor M1 from right to left, back contact 36 of relay DN and the motor field winding 16 to terminal C. Relay SN is now picked up to open back contact 37 and the motor M1 is energized as required to drive the gate arm towards its lowered position.

With controller contact 3 adjusted to open at 45 degrees as indicated by the chart of Fig. 4, the relay SN and motor M1 become deenergized at this point in the lowering of the gate arm and the gate arm would then continue in its downward movement under the influence of the bias. It is apparent, however, that controller contact 3 can be adjusted to open at some other position and the motor made to govern any pre-selected portion of the downward movement.

When the eastbound train passes beyond the intersection to vacate section D—E causing winding 11 of relay IR to be reenergized and bring about the reenergization of repeater relay TPR, the control relay XR and the winding 17 of the slot magnet are energized. With relay XR picked up to close front contacts 31 and 32, a circuit is completed for relay DN in series with the motor, current flowing from terminal B through front contacts 31 and 32 in multiple of relay XR, controller contact 4, winding of relay DN, armature 15 from left to right, back con-

tact 37 of relay SN and field winding 16 of the motor to terminal C. Relay DN is now picked up to open back contact 36 and close front contact 38 and the motor M1 is operated as required to raise the gate arm. At the 86 degree position the controller contact 5 is closed and a circuit is formed for the pick-up winding 18, current flowing from terminal B through front contacts 31 and 32 in multiple of relay XR, controller contacts 4 and 5 in series, front contact 33 of relay DN and winding 18 to terminal C. Both windings 17 and 18 being now energized, the armature 35 of the slot magnet is raised to its latching position. At the 89 degree position of the movement, the controller contact 4 is opened so that relay DN, motor M1 and winding 18 are all deenergized leaving the gate arm latched at the raised position due to the energization of the holding winding 17 of the slot magnet. Although the stick circuit for relay XR is omitted in Fig. 2, it is obvious that such stick circuit arrangement can be included in the same manner as it is included in Fig. 1, and when thus added to the apparatus of Fig. 2 the apparatus would function in the raising of the gate arm independent of the main control in the same way as described in connection with Fig. 1.

Furthermore, with controller contact 4 adjusted to open at 89 degrees in the raising of the arm and to be reclosed at the 83 degrees position in the lowering of the arm, the circuit for pick-up winding 18 of the slot magnet is held open during the lowering movement and energization of magnet SM cannot take place if a change occurs in the main control to bring about the raising of the arm when the arm is being lowered and stresses created due to stopping the movement of the arm do not fall upon the slot magnet structure.

It is clear that the apparatus of Fig. 2 will operate in response to a westbound train in a manner similar to that described in connection with an eastbound train.

Referring to Fig. 3, the apparatus is similar to that of Fig. 2 except the second relay SN is omitted and the pole changing of the motor circuit is effected at contacts of the control relay XR.

Normally, that is, when the sections D—E and E—F of Fig. 3 are unoccupied and track repeater relay TPR is picked up, the circuits for control relay XR and holding winding 17 of the slot magnet are completed so that the gate is latched at the 90 degree position, the same as explained in the previous cases.

When an eastbound train enters section D—E of Fig. 3, winding 11 of relay IR is shunted causing in turn the repeater relay TPR to be deenergized and the warning signal to be operated. Release of relay TPR at the end of its slow release period causes control relay XR and winding 17 of the slot magnet to be deenergized and the gate is unlatched and free to be moved to its lowered position. With relay XR released current flows from terminal B through back contact 23 of relay XR, controller contact 3, winding of relay DN, armature 15 of motor M1 from right to left, back contact 24 of relay XR, and field winding 16 of the motor to terminal C. Relay DN is picked up to open its back contact 39 interposed in the circuit for winding 18 of the slot magnet and motor M1 is operated as required to drive the gate arm in a downward direction. At some preselected position in the lowering of the arm and here shown as at the

45 degree position, controller contact 3 is opened to deenergize relay DN and motor M1 and further movement of the gate arm is caused by the bias force.

- 5 When the eastbound train vacates section D—E, so that winding 11 of the interlocking relay is reenergized to bring about the energization of repeater relay TPR, control relay XR and winding 17 of the slot magnet are supplied with current. With relay XR picked up current flows from terminal B through front contact 31 of relay XR, controller contact 4, armature 15 of motor M1 from left to right, front contact 32 of relay XR and motor field winding 16 to terminal C, and the motor is operated as required to raise the arm. At the 86 degree position of the gate arm the controller contact 5 is closed, and current flows from terminal B through front contact 31 of relay XR, controller contact 4, back contact 39 of relay DN, controller contact 5 and winding 18 of magnet SM to terminal C. Since both windings 17 and 18 of the slot magnet are now supplied with current its armature 35 is picked up so that when controller contact 4 is opened at the 89 degree position to open the motor circuit, the arm is latched at the raised position due to the energization of the holding winding 17. Again it is to be pointed out that due to the circuit for winding 18 including the two controller contacts 4 and 5 in series, and the construction of contact 4, winding 18 cannot be energized during the time the motor M1 is operated to power drive the gate arm in a downward movement.
- 10 35 It is apparent from an inspection of Fig. 3 that the apparatus will operate in substantially the same manner for a westbound train.
- 15 The apparatus here disclosed has the advantages that the gate arm is driven both up and down, and the downward driving of the arm by the motor is discontinued at a preselected point and dynamic braking effected so that severe mechanical shock and rebound of the arm at the lowered position are avoided. Again, the slot magnet cannot be energized during the lowering movement of the gate arm and stresses of the mechanism effected when there is a reversal in the main control of the gate during a lowering movement are taken up by the motor and not by the slot magnet. Again, the raising of the arm once initiated may be continued until the full raised movement of the arm is effected and the arm is not lowered from an intermediate position without due warning to the highway users. Also, the circuit arrangement is minimized and made simple without sacrificing safety and reliability.
- 20 40 45 50 55

Although I have herein shown and described only three forms of apparatus for control of highway crossing gates embodying my invention, it is understood that various changes and modifications may be made therein within the scope of the appended claims without departing from the spirit and scope of my invention.

Having thus described my invention, what I claim is:

1. In control apparatus for a gate mechanism which includes a reversible electric motor adapted when energized to drive the gate toward an obstructing or non-obstructing position, a circuit controller actuated by movement of the gate mechanism and a slot magnet provided with a holding winding and a pick-up winding and made effective by the energizing of its windings, the combination comprising, a first and a second con-
- 60 65 70 75

trol relay, circuit means including contacts of said first control relay to energize said second control relay and said holding winding, an operating circuit means including contacts of said second control relay to reversibly energize said motor to drive the mechanism either to the non-obstructing or the obstructing position according as said second control relay is picked up or released, a first and a second contact of said controller interposed in said operating circuit means to disconnect said motor at preselected points as the mechanism is driven toward the non-obstructing position and the obstructing position respectively; other circuit means including in series said front contact of said second control relay, said first controller contact and a third controller contact to energize said pick-up winding, said first controller contact operable to be opened subsequent to the closing of said third contact when the mechanism is driven toward the non-obstructing position and to be reclosed subsequent to the opening of said third contact when the mechanism is driven toward the obstructing position whereby stresses of the mechanism when there is a reversal of the motor during a movement toward the obstructing position are taken up by the motor, a short circuiting path including a fourth contact of said controller closed subsequent to the opening of said second contact connected across the motor to provide dynamic braking during a preselected portion of the movement of the mechanism toward the obstructing position, and means to at times energize said first control relay.

2. In control apparatus for a gate mechanism biased toward a zero degree position and operable to a 90 degree position and having a reversible motor adapted when energized to drive the gate mechanism and a controller actuated by movement of the gate mechanism, the combination comprising, a control relay, a relay DN, a relay SN, a first circuit including a front contact of said control relay and a first contact of said controller to energize said SN relay, an extension of said first circuit including a front contact of said SN relay and back contacts of said DN relay to energize said motor to operate the gate mechanism to the 90 degree position, a second circuit including a back contact of said control relay and a second contact of said controller to energize said DN relay, an extension of said second circuit including front contacts of said DN relay to energize the motor to operate the gate mechanism a preselected distance toward the zero degree position as predetermined by the opening of said second contact; a low resistance circuit including a resistor, a back contact of said DN relay and a back contact of said SN relay connected across said motor to provide dynamic braking of the motor; a short circuiting path including a back contact of each of said DN and SN relays and a third contact of said controller connected across the motor to provide heavy dynamic braking of the motor, and circuit means to at times energize said control relay.

3. In control apparatus for a gate having a mechanism including a reversible motor adapted to drive the gate mechanism, a circuit controller actuated by the gate mechanism and a slot magnet provided with a holding and a pick-up winding and made effective by the energizing of its windings, the combination comprising, a control, a pole changing and another relay; means to at times energize said control relay and said holding winding, a first circuit including a front contact

of said control relay and a first contact of said controller opened at a non-obstructing position of the gate to energize said other relay, an extension of said first circuit including a front contact of said other relay and back contacts of said pole changing relay to energize said motor to operate the mechanism to the non-obstructing position; a branch circuit path for said first circuit and including said front contact of the control relay, said first contact of the controller and a second contact of the controller to energize said pick-up winding; a second circuit including a back contact of said control relay and a third contact of said controller opened at a preselected point in the movement of the gate to an obstructing position to energize said pole changing relay, an extension for said second circuit including front contacts of the pole changing relay to energize said motor to operate the mechanism toward the obstructing position to a point preselected by the opening of said third controller contact; and other circuit means including a back contact of said pole changing relay, a back contact of said other relay and a fourth contact of said controller to provide dynamic braking of the motor.

4. In control apparatus for a gate mechanism operable to an obstructing and to a non-obstructing position and having a reversible motor adapted when energized to drive the mechanism, a circuit controller actuated by movement of the mechanism and a double winding slot magnet made effective by the energizing of its windings, the combination comprising, a first and a second control relay, circuit means including a front contact of said first control relay to energize said second control relay and a holding winding of said slot magnet, an operating circuit means including a front and a back contact of said second control relay to reversibly energize said motor to drive the gate mechanism either toward its non-obstructing or obstructing position according as said second control relay is picked up or released, a first and a second contact of said controller interposed in said operating circuit means to deenergize said motor as it drives the gate mechanism toward the non-obstructing and obstructing positions respectively; other circuit means including in series said front contact of said second control relay, said first contact of said controller and a third contact of the controller to energize a pick-up winding of said slot magnet; said controller of a construction for said third controller contact to be closed prior to the opening of said first controller contact when the motor is driving the mechanism toward the non-obstructing position and for said first controller contact to be reclosed subsequent to the opening of said third controller contact when the motor is driving the mechanism toward the obstructing position, and means to at times energize said first control relay.

5. In control apparatus for a gate mechanism operable to an obstructing and to a non-obstructing position and having a reversible motor adapted when energized to drive the mechanism, a circuit controller actuated by movement of the mechanism and a slot magnet provided with a holding and a pick-up winding and made effective by the energizing of its windings, the combination comprising, a first and a second control relay, a first and a second pole changing relay, circuit means including a contact of said first control relay to energize said second con-

trol relay and said holding winding; a first operating circuit including a front contact of said second control relay, a first contact of said controller, a winding of said first pole changing relay, said motor and a back contact of said second pole changing relay to energize the motor to drive the mechanism toward the non-obstructing position; a second operating circuit including a back contact of said second control relay, a second contact of said controller, a winding of said second pole changing relay, said motor and a back contact of said first pole changing relay to energize the motor to drive the mechanism toward the obstructing position; another circuit including said front contact of said second control relay, said first controller contact, a third controller contact and a front contact of said first pole changing relay to energize said pick-up winding of the slot magnet, and means to at times energize said first control relay.

6. In control apparatus for a gate mechanism operable to an obstructing and a non-obstructing position and having a reversible motor adapted when energized to drive the mechanism, a circuit controller actuated by movement of the mechanism and a slot magnet provided with a holding and a pick-up winding and made effective by the energizing of its windings, the combination comprising, a first and a second control relay, another relay, means including a contact of said first control relay to energize said second control relay and said holding winding; a first operating circuit including front pole

changing contacts of said second control relay and a first contact of said controller to energize said motor to drive the mechanism toward the non-obstructing position; a second operating circuit including back pole changing contacts of said second control relay, a second contact of said controller, and a winding of said another relay to energize the motor to drive the mechanism toward the obstructing position; another circuit including one of said front pole changing contacts of the second control relay, said first controller contact, a back contact of said another relay and a third contact of said controller to energize said pick-up winding; and means to at times energize said first control relay.

CARL L. GOODLIN.
